LOCK FOR REGISTER FLASH MECHANISM

William G. Orth and Thomas O'Connor, Dayton,
Ohio, assignors to Ohmer Fare Register Com-
pany, Dayton, Ohio

Application December 29, 1928. Serial No. 329,133

4 Claims. (Cl. 235—24)

The object of this invention is to provide a positive locking means for the flash mechanism of a register and for purposes of illustration we have shown such a lock as applied to the type 5 of register disclosed in the application of Albert S. Wheelbarger, Serial Number 236,094, filed November 28, 1927.

In the drawing—

Fig. 1 is a side elevational view of part of such 10 a register showing our improved locking mechanism incorporated therein.

Fig. 2 is a side view of the opposite side from that shown in Fig. 1, and

Fig. 3 is a detail view of the flash setting cam 15 and the lever directly controlled thereby.

There are a plurality of setting levers 1, only one of which is shown. Each of the levers 1 is connected to a gear 2 which drives a gear 7 operatively connected to a gear 9 which drives a 20 gear 10 secured to the indicating drum 11 which is provided with suitable characters or figures to indicate the class of transaction or amount thereof.

The flash is mounted on the shaft 53 and consists of end plate 54 and a conventional end plate 25 on the opposite side thereof, which end plates are connected by two plates 56 on which is written the words "not registered" or similar indicia which indicates both to the front and to the 30 rear of the machine that the registration has not been made. As soon as the registration is made the flash is moved clockwise as viewed in Fig. 2 so as to move the two plates 56 into the position shown in Fig. 2. In this position the 35 indicia on the flash is moved out of alignment with the sight openings 50 in the front and rear of the casing 51.

The shaft 57 is provided with a plurality of levers 58 only one of which is shown. Each of 40 these levers 58 carries a roller 59 which engages the teeth of its corresponding gear 2 mounted on the shaft 60. Each lever 58 is actuated so as to hold its roller 59 in engagement with the teeth of the gear 2 by means of a spring 61. An arm 45 62 is rotatably mounted on the shaft 57, there being one such arm on each side of the machine, which arms are connected by a cross bar 64 lying immediately in front of each of the levers 58. Secured to one of the arms 62 is an arm 65 50 connected to a spring 67 which in turn is secured to any fixed part of the machine. The spring 67 by pulling upwardly on the arm 65 holds the cross bar 64 in engagement with the levers 58. The arm 65 is provided with a pin 68 which 55 engages a bell crank lever 69 mounted on a pin 70

in the right side wall of the frame. The bell crank lever 69 has an upwardly extending arm 55 as clearly shown in Fig. 1 so as to engage with the seat 71 or 72 in the plate 54 of the flash. These two seats are connected by a sloping surface 60 73.

The machine is operated through a crank handle 74 connected to a gear 75 which drives a gear 76 on a shaft 77 which drives a Geneva gear 78 which drives a Geneva pinion 79 on a shaft 80 65 which Geneva pinion 79 drives a gear 81 on a shaft 82. The Geneva gear 78 and Geneva pinion 79 are so constructed that the shafts 80 and 82 are rotated only during the last part of the revolution of the crank handle 74 and the pinion and gear 81 70 75 make one complete revolution each time the machine is completely operated. The shaft 82 is provided with a cam 83 which has a cut-away portion 84 forming a recess in which normally lies the lower end of lever 85 pivoted on a rod 86. The upper end of the lever 85 engages one arm of a bell crank lever 87 pivoted on a cross bar 88. A spring 89 constantly tends to urge this lever in a counter-clockwise direction as viewed in Fig. 1. The upper end of the bell crank lever 87 is bent 80 outwardly so as to extend through an aperture 90 in the casing. The upper end of the bell 90 95 crank lever 87 carries a pin 91 which engages between two arms 92 in the plate 54 of the flash.

In operation the respective levers 1 are moved 85 so as to rotate its corresponding drum to the desired position. As soon as anyone of these levers 1 is moved, the teeth of its corresponding gear 2 will cause the lower end of one of the levers 58 to move outwardly or away from the said gear. 90 This movement will move the cross bar 64 in a counter-clockwise direction as viewed in Fig. 2 or in a clockwise direction as viewed in Fig. 1 so that the pin 68 carried by the lever 65 will engage the bell crank lever 69 and rock the same clockwise 95 as viewed in Fig. 1 so as to disengage the upper end 55 of the said lever 69 from the seat 71 whereupon the spring 89 will rotate the bell crank lever 87 in an anti-clockwise direction and thereby rotate the flash in a clockwise direction 100 as viewed in Fig. 1 or an anti-clockwise direction as viewed in Fig. 2 thereby moving the plates 56 so that the indicia thereon is in alignment with the sight openings 50 in which position the flash is stopped by the end 55 of the lever 69 engaging 105 the seat 72. This shows that the amount set up has been indicated but it has not in fact been registered for the registration will not take place until the crank handle 74 has been operated, or if electrically operated, until the shaft 77 has 110

been rotated one complete revolution. As soon as it is rotated the shaft 82 will likewise be rotated and the lever 85 will be actuated by the cam 83 so as to move the lever 87 into the position shown 5 in Fig. 1 and thereby rotating the flash so as to move the plates 56 out of alignment with the sight openings 50. The seat 71 has thus been moved above the upper end of the lever 55 and the spring 93 moves the lever 55 into a position to engage 10 the seat 71.

In rapidly operating the machine, however, it has been found that sometimes the spring 93 does not properly hold the end 55 of the lever 69 in its proper seat. The principal object of this invention is to provide a positive locking means so that the lever 69 cannot be displaced. To this end we have provided a square lug 94 on the lever 69 approximately midway between the fulcrum pin 70 and the extreme upper end thereof. We have 15 also provided a cam 95 which is clearly shown in Fig. 1 which cam is rigidly secured to the shaft 77, which it will be remembered, makes one complete revolution upon each operation of the machine. A push rod 96 has a pin 97 and slot 98 20 connection with the side wall of the machine. The lower end of the push rod 96 rides on the periphery of the cam 95 and the upper end 99 is adapted to engage the lug 94 until the cam 95 has practically completed its revolution, at which 25 time the cam point 100 has passed beyond the lower extremity of the push rod 96 and spring 101 pulls the push rod 96 downwardly thereby disengaging the upper end 99 thereof from the lug 94.

It will therefore be noted that whenever one 30 of the levers 1 is moved the flash is instantly thrown to show that the machine has not been operated, that is the registration has not been made. It has simply been indicated. When the registration has been made, however, by the rotation 35 of the shaft 77, the flash is moved to show that the registration has been made and with the positive locking means which we have shown and described it is impossible for the flash mechanism to be jarred so as to indicate that the registration 40 has not been made when it has. Having now described our invention,

We claim:

1. In a register, a setting means a two position flash controlled by said setting means, a lever adapted to engage said flash in both of its positions, means to lock said flash through said lever so that it cannot be moved from non-obscuring position during actuation of the register, and means to unlock said flash when the register has completed a registration so that the register can be adjusted to set up a succeeding registration. 80

2. In a register, a flash having two seats thereon, a lever adapted to engage normally one of said seats, setting means whereby said lever may be disengaged from the last mentioned seat, 90 means to shift thereupon said flash so as to bring the other of said seats into position to be engaged by said lever, operating means, means whereby the operating means when being operated shift said flash so as to bring the normally engaged seat into position to be engaged by said lever, and means to thereafter positively lock said lever against any movement until the operating means has completed its operation. 95

3. In a register, a flash having registered and 100 non-registered positions, a setting means, a lever to hold said flash normally in its registered position, means whereby said flash is shifted to its non-registered position when said setting means is operated, an operating means, means to shift 105 said flash to its registered position so that it will be engaged by said lever when said operating means is being operated, and means to lock thereafter said lever against displacement until the completion of the operation of the operating 110 means. 100

4. In a register, operating means for the register, a flash having a seat thereon corresponding to the operated position of the flash, a lever engaging said seat, a lug carried by said lever, and 115 a slide adapted to be actuated by the operation of said register and to engage said lug and hold said lever against displacement until the operating means for the register has completed its operation. 120
